UNITED STATES PATENT OFFICE.

GEORGE GEER, OF RICHMOND, VIRGINIA, ASSIGNOR OF ONE-HALF TO
CHARLES E. BUCK, OF SAME PLACE.

CIGARETTE-MACHINE.

SPECIFICATION forming part of Letters Patent No. 593,158, dated November 2, 1897.

Application filed October 25, 1895. Serial No. 566,885. (No model.)

To all whom it may concern:

Be it known that I, GEORGE GEER, a citizen of the United States, residing at Richmond, in the county of Henrico and State of Virginia, have invented certain new and useful Improvements in Cigarette-Machines, of which the following is a specification.

The cigarette-machine to which the invention that is herein described pertains is of that general class or type in which the finely-cut tobacco or stock is fed in charges into molds or matrices in which it is given a cigarette shape or form as a formed charge of tobacco ready to receive the wrapper while within the mold and become a cigarette.

A leading object of the invention is to provide cigarette-machines in which the charge-forming molds are arranged in a circular series, revoluble by a head which carries the molds and presents them in regular sequence to a stock-feeding mechanism, thence to the mechanism for placing the wrappers on the charges while in the molds, thence to the mechanism for ejecting the cigarettes, and thence again to the stock-feeding mechanism.

A further object of my invention is to provide charge shaping or forming molds of such construction that the radial part thereof at one side of the slot-opening can be swung away from the other radial part to permit of opening the mold.

A further object of my invention is to provide means for opening the molds and for feeding the unformed charges of stock thereinto.

Another object of my invention is to provide a cutter which consists of a frame that has only a vertical reciprocating movement and which carries a cutter-blade with it, which blade is hinged to have a forward-swinging movement and which will sever the charges of tobacco from the sheet thereof and also feed or thrust said severed charges into the molds.

A further object of my invention is to provide means for rotating the formed charge of stock in the mold and for transfixing it there while the grippers for rotating it are inserted therein.

A further object of my invention is to provide improved means for inserting the wrapper in the open-side molds and into engagement with the formed charges therein.

A further object of my invention is to provide improved means for ejecting the cigarette from the molds, and, further, to provide, in combination with the ejector, a mold-opening device for freeing the cigarette from the sides of the mold to render it easily removable; and a still further object of my invention is to provide a table for receiving each cigarette as it is ejected from the mold and for doffing them singly from the machine as they are received without bending, crushing, or otherwise damaging their forms.

The novel structural peculiarities, novel organizations of parts, novel combinations of parts, and the separate and collective operations of parts which are involved in carrying out the foregoing recited leading objects of my invention are hereinafter described and made the subject-matter of claims hereto appended.

In carrying out these leading objects of my invention in a concrete form or machine further improvements have been evolved than have been hereinbefore recited, which improvements consist in novel structural peculiarities, novel organizations of parts, and novel combinations of parts, the separate and collective operations of which parts, their structural peculiarities, novel organizations, and novel combinations are hereinafter fully described and respectively made the subject-matter of claims hereto appended.

Mechanism embodying the preferred structural peculiarities of the different parts, the preferred disposition of the different parts, and the combinations forming the subject-matter of my improvements are illustrated in the accompanying drawings, in which—

Figure 1 is a top plan of a cigarette-machine embodying my improvements with the shown parts in their normal relative positions as when at rest; Fig. 2, a front side elevation or elevation of the side at which the wrappers are fed into the molds, the parts in same relative positions as at Fig. 1; Fig. 3, an elevation showing the left-hand side of the machine, as shown at Fig. 1, the parts in same relative positions as at Fig. 1; Fig. 4, a sectional elevation of the feed-table and rear elevation of the balance of the machine, the parts in same relative positions as at Fig. 1;

Fig. 5, a side elevation of the upper part of the right-hand side of the machine or side opposite that shown at Fig. 3, the parts in same relative positions shown at Fig. 1; Fig. 6, an enlarged sectional elevation in line 6 6 in Fig. 2 and elevation of the sector-gear for rotating the grippers and other adjacent parts, the parts, as shown by full lines, in same relative positions as at Figs. 1, 2, 3, 4, and 5; Fig. 7, an enlarged oblique sectional plan in line 7 7 in Fig. 6; Fig. 8, an enlarged central sectional elevation in line 8 8 in Fig. 2, the parts shown in different relative positions from Figs. 1 to 7, both inclusive; Fig. 9, a sectional elevation in line 9 9 in Fig. 11 and in same plane as one side of the molds and their carrying-head. This figure shows the presser-rollers removed and the presser-block turned upward out of working position. Fig. 10 is a sectional elevation in line 10 10 in Fig. 9. Certain parts are shown in elevation in this figure that are not shown in Fig. 9. Fig. 11 is a sectional elevation in line 11 11 in Fig. 8, shown with the presser-block, presser-rollers, and outer side parts removed; Fig. 12, a sectional elevation in line 12 12 in Fig. 1, parts broken away, and presser-block and rollers removed; Fig. 13, a sectional elevation in same plane in Fig. 2 as is Fig. 8, but showing the parts in different relative positions from what is shown at Fig. 8; Fig. 14, same sectional elevation as Fig. 13, but showing the parts in different relative positions from what is shown at Figs. 8 or 13; Fig. 15, an enlarged front elevation of a portion of the parts shown at Fig. 2, but in different relative positions from what is shown at Fig. 2; Fig. 16, a sectional plan in line 16 16 in Fig. 10; Fig. 17, a sectional elevation in line 17 17 in Fig. 15, a side elevation of the doffer-table and its immediate actuating mechanism, and a side elevation showing the opposite side of crank-arm 27, pawl 28, and spring 29 from their sides, as shown at Figs. 12 and 21; Fig. 18, an end elevation of the doffer-table and sectional elevation of parts in the line 18 18 in Fig. 17; Fig. 19, a sectional elevation of a mold, part of one arm of its carrying-head, the fork for rotating the formed charge in the mold, also of the formed-charge transfixing or holding fork, and side elevation of the mechanism for tripping and holding the charge-holding fork. Other intervening parts are not shown. Fig. 20 is the same as Fig. 19, but shows the parts in different relative positions from what is shown at Fig. 19; Fig. 21, side elevation of a mold, of the stop for arresting and releasing the motion of the mold-carrying head, shown in its tripped position, and of the stop-tripping mechanism; Fig. 22, a sectional elevation of a mold and of the formed-charge rotators in line 22 22 in Fig. 19; Fig. 23, a sectional elevation of a mold, charge therein, of the wrapper-table and other adjacent parts, and side elevation of the wrapper-side tucker or feeder and other adjacent parts; Fig. 24, same as Fig. 23, but

the parts in different relative positions from what is shown at Fig. 23; Fig. 25, a front elevation, partly broken away, of the wrapper-guide and feed-roller and its bracket-bearing; Fig. 26, a front elevation of the cutter, presser-block, and other adjacent parts seen from their sides, confronting the rotary head and molds. The cutter in this figure is shown in its raised or elevated position, and part of the framework is shown as removed to show the presser-roller beyond. Fig. 27 is a sectional plan in line 27 27 in Fig. 26, the cutter assumed to be in its lowest position, as shown at Fig. 13; Fig. 28, a top plan, partly broken away, of the friction-clutch gearing and ratchet-gearing between the main power-shaft and the cutting, feeding, pressing, and other parts of the machine; Fig. 29, an enlarged plan of part of Fig. 28, broken away to show other parts; Fig. 30, same as Fig. 29, but parts in different relative positions from what is there shown; Fig. 31, a side elevation of the parts shown at Fig. 28 with the two pinions removed and the parts in rear thereof in same relative positions as in Fig. 30; Fig. 32, a rear elevation of the pinion shown at Figs. 29 and 30; Fig. 33, a sectional elevation of the pinion 5 and disk 38 in line 33 33 in Fig. 31; Fig. 34, an enlarged top plan of the stock-feeding table; Fig. 35, a perspective of the tucker and adjacent mold as formed for square wrappers; Fig. 36, a perspective of the lining mechanism for the charge-rotators.

The reference letters and numerals herein used indicate, respectively, the same part in the different figures of the drawings. The curved arrows indicate without further description the direction of movements of parts, and where single figures of the drawings are referred to in the descriptive part of the specification such reference is only intended to point out a figure in which the specific parts referred to are well shown, and other figures may show the same part.

The letter A designates the side frame-bars, and a transverse bars, of the framework of my machine, which framework may be of any suitable construction.

Continuous rotary motion while the machine is in operation is given to the driving-shaft 1, which for that purpose receives the action of any suitable power through the pulley 2, Fig. 2, or otherwise, and the pinion 3, fixed to said shaft, Fig. 3, in turn gives continuous rotary motion, through the pinion 4, to a pinion 5, loosely mounted on a cam-shaft 6, and also by same means gives continuous rotary motion to a pinion 7, loosely mounted on the mold-carrying shaft 8. A head 9, fixed to the shaft 8, has a series of arms 10 projecting radially therefrom. In the present example four such arms are shown, Figs. 8 and 9, but their number may be varied by adapting other parts thereto. Each of the arms 10 consists of a jaw 11, fixed to the head 9, and a jaw 12, hinged to the same head and held in close contact with the fixed jaw 11 by a spring 13.

The confronting faces of the two jaws of the arms 10 have each at its outer end part a transverse groove 15, parallel with the shaft 8 and coincident when the jaws are closed, whereby they form a cavity or mold 16 of substantially circular form in its cross-section and slightly open at its outer side, where the two jaws do not quite meet, and also preferably about one-fourth of an inch longer than a completed cigarette, so that when trimmed off at their ends the cigarettes will be of standard lengths. In these molds the unformed charges of tobacco stock or filler are formed into cylindrical charges each ready to receive its wrapper while still within the mold, all as hereinafter described. A diaphragm 17 is fixed at one end to one of the jaws 11 or 12, and its other end extends into a recess in the other jaw, Fig. 24, so as to slide out and in therein, respectively, when the jaws are opened or closed and at all times prevent any of the charges of tobacco stock from escaping from either mold into the interspace between the jaws 11 and 12. A series of perforations 18 extend through one of the jaws, in this instance the fixed jaw 11, into the cavity or mold for purposes hereinafter described.

A detent or mold-stop 19, fixed to an oscillating shaft 20, is by a trip mechanism hereinafter described intermittently swung into the path of the outer ends of the arms 10, and each arm 10 as it follows another in regular sequence comes into contact with the detent 19, Figs. 13 and 14, whereby the rotation of the shaft 8 and revolution of the molds is arrested and said parts held at rest while a charge of tobacco stock is fed to one mold, the wrapper applied to the formed charge in another mold, and the ejector operated in another, and this detent 19 is tripped into and out of engagement with said arms successively and the revolute movement of the molds made intermitting by said tripping mechanism, and by means of an ordinary friction-clutch, in which in the present instance one member thereof—a disk 21 fixed to the mold-shaft 8—is kept in frictional contact with the other member—a loose pinion 7—by means, Fig. 28, of an interposed leather annulus 22 or other suitable means fixed to said disk or to the pinion 7. The force of this frictional contact is adjustable by adjusting the stub-screw bolt 23, Fig. 1, which screws into the end of the shaft 8 to force the spring-plate 24 into more or less forcible contact with the outer face of the pinion 7, and thereby hold said pinion in such frictional contact with the disk 21 that the rotation of the driving-shaft 1 will rotate the mold-shaft 8 and carry the molds around in their orbital paths until one of the molds comes in contact with the detent 19, when the frictional contact between the disk 21 and the pinion 7 will permit said pinion to continue revolving, while the disk 21, shaft 8, and the molds remain at rest. The detent 19 will thus hold the shaft 8 and the molds until by the foot of an operator on the foot-piece 27 $\frac{1}{2}$ at the lower end of the longer

arm of the treadle 26 said treadle is given its complete forward throw in the direction shown by the full-line arrow at Fig. 17 and has about completed its return throw in the direction shown by the dot-line arrow at Fig. 12, as hereinafter described. The treadle 26 is in form a bell-crank lever and is journaled at its bend on the drive-shaft 1, from which its shorter arm projects radially, as a crank-arm 27, Figs. 12 and 17. A push-pawl 28, pivoted to a slightly-projecting part of the arm 27 and projecting upwardly therefrom, is held against backward movement, Fig. 17, by a stop 30, with which an arm projecting from the pawl 28 comes in contact, while permitted to yield in an opposite direction for operation on a ratchet-wheel, as hereinafter described. As the treadle 26 completes its return throw the pawl 28 is brought into contact with one of the teeth of the ratchet-wheel 31, Fig. 12, and rotates said ratchet-wheel the angular distance of one of its teeth to the position shown at Fig. 21. In this last-described movement of said ratchet-wheel another tooth thereof acting as a tappet presses back the outer end of a crank-arm 32, Fig. 21, the proximate end of which crank-arm is fixed to the shaft 20, so that said backward movement of the crank-arm 32 swings the detent 19 from beneath the mold, and thereby permits the shaft 8 to commence revolving the molds through the frictional clutch-gear between the constantly-rotating pinion 7 and the disk 21. Immediately after the escape of a mold from the detent 19 by the action of its tripping mechanism—treadle 26, pawl 28, and arm 32—the tooth of the ratchet-wheel 31 last engaged with the arm 32 being moved from beneath said arm 32 being moved from beneath said arm 32 the spring 33 will immediately retract or swing the arm toward the ratchet-wheel into its normal position, Fig. 12, behind the tooth which last acted on it, and this movement of the arm 32 will through the medium of the shaft 20 swing the detent 19 immediately into position for contact with the next succeeding mold to that last acted on by it.

Each partial rotation of the shaft 8, hereinbefore described, turns the disk 21 one-fourth of a complete rotation, as hereinbefore described, and near the termination of such movements of the disk 21 the tappets 34, projecting radially from the disk 21, Fig. 31, successively come in contact with the inclined or cam-faced side of the head 35 on one end of a bell-crank lever 36, which is pivoted at its bend to the framework, and force said bell-crank lever into the position shown by dot-lines at same figure, thus raising the end of the bell-crank trip or lever opposite the head 35 out of the notch 37 in the periphery of the disk 38 to release said disk and at the same time raising the two-arm fork 39, carried by the arm 36, from contact as a detent, as shown at Fig. 30, with a laterally-moving spring-actuated pawl 40, as seen at Fig. 29, and thereby permitting said pawl to move laterally into engagement with one of

the notches or ratchet-teeth 41 in the adjacent face of the pinion 5, Fig. 29. The pawl 40 is seated in an annular groove 42 in the face of the disk 38, and one of its ends is fixed to said disk, and while its other end is engaged with one of the ratchet-teeth 41, as described, so the rotation of pinion 5 will therewith simultaneously rotate the disk 38. Thus at each one-fourth of a full rotation of the disk 21 the trip 36 is operated to engage the two members 5 and 38 of the clutch D, and they remain so engaged and rotate simultaneously until the disk 38 and the cam-shaft 6 make a complete rotation, when the longer end of the trip is drawn down by a spring d to engage with the notch 37, release the pawl 40, Fig. 30, and arrest the rotation of the disk 38 and shaft 6, with the parts in the relative positions shown by full lines at Fig. 31, in which positions they remain at rest until again rotated by the same means.

Each intermittent but complete rotation of the cam-shaft 6 operates the feed-belt, the vertically-reciprocating and forwardly-swinging cutter, the presser-block, the charge-compacting arms, and the mechanism for opening the molds successively for receiving their respective charges of tobacco stock, as follows: A cam 42 on the cam-shaft 6, Fig. 12, coming in contact with the downturned end 43 of the connecting-rod 44, which is in the path of said cam, forces it forwardly and thereby swings the crank-arm 45 into the position shown by dot-lines at same figure. The crank-arm 45 is loosely mounted on the outer end of a shaft 46, to which is fixed a ratchet-wheel 47, pinion 48, and a belt feed-roller 49, Fig. 26. A pawl 50, pivotally mounted on the crank-arm 45, is held in contact with the ratchet-wheel 47 by a spring e, so that as the crank-arm 45 is swung into said dot-line position it will impart a partial rotation to the ratchet-wheel 47, pinion 48, feed-roller 49, and also to a pinion 51, geared with pinion 48 and fixed on the outer end of a shaft 52, on which is mounted, Fig. 8, another belt feed-roller 53, same figure. The feed-belt G is further supported on rollers 54, the outer one of which is carried in a frame and is adjustable in an ordinary manner to tighten and loosen the belt by a screw-bolt g. The belt is driven by frictional contact with the rollers 49 and 53. The bearings 55 for the upper roller are fixed, Fig. 4, and the bearings 56 are adjustable vertically on rods 57, pendent from the bearings 55. The bearings 56 are held in yielding frictional contact with the belt by means of washers and springs 58 and stud-bolts 59, screwed into the lower end of the rods 57 for the purpose of adjusting said frictional contact as desired. The intermittent movement given, as described, to the ratchet-wheel 47 will give same movement to the feed-roller 49 and feed the upper part of the feed-belt forwardly toward that mold which in its interval of rest is in a horizontal position and facing the belt. The movements

of the feed-belt are also intermittent, and the extent of each movement is such as to feed the desired quantity or charge of tobacco stock to the molds for a single cigarette by feeding forwardly a regulated sheet 60 of such stock contained between the side guards and end guard 61. (See Figs. 4 and 34.) The extent of each intermitting movement of the feed-belt is also adjustable by means of a series of holes 63 in the crank-arm 45 and a bolt 64 for varying the quantity of stock for each cigarette.

A latch-bar 65, hinged at one end to the connecting-rod 44, has a notch 65₁, which can be engaged with the mold-shaft 8 by drawing the rod 44 toward said shaft, as shown by dot lines at Fig. 12, and thereby holding the turned-down end of the rod 44 out of the path of the cam 42, whereby the operation of the feed-belt will be stopped as may be desired, and when so stopped the molds will continue revolving until the charges they contain will all be wrapped and ejected from the molds. While the feed-belt is in operation the latch-bar is turned back, as shown by full lines at same figure.

The cutter-blade 72, the swinging part or frame 68, to which it is fixed, and the vertically-reciprocating part or frame 67, to which the swinging frame is hinged, I have collectively termed a "cutter" and designated the same by the numeral 66. (See Figs. 4, 8, 13, 14, and 26.) The part or frame 67 is mounted or suspended as hereinafter described, so that it may be reciprocated vertically, and in the present instance is formed of a top part or bar 73, pendent side parts or bars 74, brackets 75, and springs 76, connecting said brackets and the lower parts of the bars 71, Figs. 4, 8, 13, 14, and 26. The part 68 in the present instance is formed of an upper bar 69, lower bar 70, pendent side bars 71, and a cutter-blade 72, removably fixed to the bar 70. The part 68 is hinged at its upper side to the reciprocating frame 67, so that it is carried up and down or reciprocated with said frame 67, while free to swing forwardly or toward the molds and return independently of said reciprocating frame. It will be evident that the cutter-blade 72 moves up and down and swings forwardly with the swinging frame 68, to which it is fixed. The lower end of each side part or pendent bar 74 is pivotally connected by a link 77 with the machine-frame, and springs 78, Figs. 13 and 14, connected with said links and parts of the frame above, exert an upward force action on the bars 74 and thereby yieldingly hold the entire cutter 66 in its highest or normal position, as seen at Figs. 5, 8, and 12. Arms 79, hinged at their distal ends to the part 67, are pivotally connected or hinged at their other ends to the upper ends of standards b, which project upwardly from and form parts of the framework. The swinging arms 79 act as guides for the upper parts of the cutter 66, and the link 77 acts as a guide for its lower end, while the two guides

thus aline the reciprocating movements of the frame 67.

At their lower ends the pendent parts 74 are enlarged laterally, and each carries a laterally-projecting stud 80, each of which studs projects into the path of a respective cam 81, fixed to the cam-shaft 6. During each rotation of the shaft 6 the cams 81 come in contact with the respective studs 80 and force the cutter 66 downwardly, Fig. 13, so that the cutter-blade 72 will sever a regulated quantity for a charge from the stock 60. Immediately after the part 68 and its cutter-blade 72 has reached its lowermost position to the bed-plate 62 cams 83 on the cam-shaft 6, coming in contact one with each of the pendent arms 71, which are connected with and form a part of the part 68, force or swing the part 68 and its cutter-blade 72 forwardly toward the now open mold 16, facing said blade, Fig. 14, and thereby force the severed tobacco or charge into said open mold, when the arms 71 now escaping from the cams 83 the springs 76 will retract or draw back the part 68 to its normal position against the part 67, and the projecting stud 80 now escaping from the cam 81 the springs 78 will force the entire cutter 66 up to its normal position, at which point its upward movement is arrested by contact of a cam 84, Fig. 26, with the stud 80. The cams 84 are fixed to the cam-shaft 6, opposite to and in same plane of rotation, respectively, as the cams 81. (See Fig. 11.) The molds are successively opened for receiving their respective charges of tobacco, as last described, by means of a pendent spring-plate 85, the lower end of which is in the form of a tapered spring-catch 86, Fig. 9, and the upper end of which is fixed to one end of an arm 85½, the other end of which is fixed to a short shaft 87, journaled in one of the standards b, and provided at its other end with a crank-arm 88, the lower end of which lies in the orbital plane of revolution of a cam 89, fixed to the cam-shaft 6. While the cam 89 is not acting on the arm 88 the lower end of the spring-plate 85 is in such position that one of the stud-pins 90, one of which projects laterally, Fig. 10, from the outer end of each hinged jaw 12, will come in contact with the tapered side of the catch 86, and, forcing it backwardly, will pass it, when the resiliency of the spring-plate 85 will immediately restore it to its normal position, with the catch 86 below a stud-pin 90 just as the molds have come to rest. At this moment the cam 89, acting on the crank-arm 88, will raise the spring-plate 85 and thereby raise the hinged jaw 12 and open the mold, Fig. 14. Before the molds begin to revolve and after each one has received its charge of tobacco, as described, the cam 89 will escape from the crank-arm 88 and the spring 91, Fig. 8, will restore said crank-arm and spring-plate to their normal positions. The molds commencing to revolve the stud-pin 90 last engaged with the catch 86 will be carried away from said catch, and

the next succeeding stud-pin will engage the catch in same manner as before described.

When the tobacco stock for a cigarette is thrust by the part 68 and its cutter-blade into a mold, a slight portion thereof will project from the end of the mold, and to push this projecting part into the mold and also for the purpose of slightly compacting the charge at each end of the mold 16 I provide the compacting-arms 92, Figs. 26 and 27, which are connected at their outer ends by hinges 93, one to the outer side of each ledge 61½, so that they can swing outwardly. The ledges 61½ form the inner ends of the sides 61. Each compacting-arm 92 is held in its normal position with its inner downturned end 94 resting against an end of a mold 16 by a spring 95, (see Fig. 11,) one end of which is connected with a stud-pin 96, projecting laterally from near the rear end of the compacting-arm, and its other end connected with a pin projecting from the outturned bottom of the adjacent ledge 61½, and they remain in such positions until the part 68, with its cutter-blade 72, is lowered to sever the charge of tobacco, when the lugs 97, pendent from the bar 70, Fig. 26, come in contact, respectively, with the inclined cam-faces of the grooves 98, Fig. 11, in the compacting-arms, Fig. 27, and as said lugs descend with the cutter they force the compacting-arms outwardly into the positions shown at Fig. 27, and so hold them while the cutter-blade 72 swings forwardly and forces the charge of tobacco into a mold. As the cutter-blade and lugs 97 rise the springs 95, acting on the stud-pins, force the hinged compacting-arms again to their normal positions. Trough-shaped plates 99, fixed to the inner end of the bed-plate 62, one at each end of the molds, so that the molds pass between them, receive the projecting ends of the charges, prevent their falling, and act as guide-plates for said projecting ends as they are forced into the molds.

A weighed quantity of tobacco stock 60 is placed on the feed-table, Fig. 34, between the outer end thereof and the mark 100, Fig. 34, and as this is intermittently fed forward it first passes beneath the heavy metallic rollers 101, which are journaled to rise and fall in slots 102 in the ledges 61½. The rollers 101 by their gravity slightly compress the stock, which thence passes intermittently beneath the heavy metallic presser-block 103. Said presser-block is carried by arms 104, one at each side thereof, and each of said arms is hinged at its rear end to the bed-plate 62 and at its forward end is fixed to an adjacent arm 105, which projects laterally from the presser-block and thence downwardly into the path of a cam 106, fixed on the cam-shaft 6, Fig. 26. The arms 105 contact with their respective cams 106, and said cams force them and the presser-block upwardly immediately before the feed-belt is acted on to feed the stock forwardly. The feed-belt is then acted on and feeds the sheet of stock forward a distance

equal to supplying a charge of stock for a cigarette, which passes beneath the presser-block, Fig. 8. The cams 106 then passing from contact with the arms 105 allow the 5 presser-block to fall and by its gravity compress the now advanced unpressed part of the sheet of stock to same extent as that in advance of it, as shown at same figure. At 10 this instant the descending cutter 66 brings the pendent foot 107 into contact with the presser-block and forces it down to the position shown at Fig. 13.

The pendent foot 107 is yieldingly connected with the upper bar 67, Fig. 4, by means 15 of stud-bolts 108, which pass through slots 109 in the bar 67 and screw into the foot 107 and springs 110, mounted on same bar, with their ends resting on said stud-bolts. The foot 107 is alined by stud-bolts 111, which pass through 20 slots 112 therein and are screwed into the bar 67. The presser-block has an inclined blade and cutter-guide 113 at its lower front side which, when it descends, partly severs the sheet of tobacco stock, Figs. 13 and 14, by the 25 force action applied to the presser-block by the cutter 66 through the instrumentality of the pendent foot 107. When in its lowest position last described, the blade and cutter-guide 113 so nearly approaches the shoulder 30 114 that the tobacco beneath it is very tightly compressed, so that it will be cleanly and completely severed by the descending cutter-blade 72, when it descends, as hereinbefore described, and in such descent the cutter-blade 35 72 slides closely against the adjacent side of the blade and cutter-guide 113 and against the adjacent side of the shoulder 114, Figs. 8 and 13, in the bed-plate 62, and which shoulder aids in the shear action of the cutter-blade 72. The presser-block may be turned 40 back into the position shown at Fig. 9 when it is desired to examine the cutter-blade 72 or remove it for access to other parts.

The fork for transfixing or holding the 45 charges within their respective molds is operated as follows: A rock-shaft 115, journaled in sleeve-bearings 116 and 117, Fig. 15, which bearings are supported by and on opposite sides of a standard *b*, has fixed to its inner 50 end a radial arm 118 and to its outer end a pawl 119. The upper end of the charge-transfixing fork 120, Fig. 15, is hinged to the outer end of the radial arm 118, Fig. 8, and at its lower end or head 121 carries a series of pend- 55 ent prongs or tines 122, which conform in their spacing and location to the series of holes 18 in the jaws 11 of the molds, Fig. 22. The transfixing-fork 120 is held in alinement to enter the holes 18 properly by a spring 123, which is connected thereto at one end and at 60 its other end to the arm 118, and by a stoppin pin 124, Fig. 8, which projects downwardly and outwardly from the arm 118.

While the treadle 26 is in its normal position, Fig. 3, with the outer end of its arm 27 in its highest position, the link-bar 125, which is pivotally connected at its lower end to the

outer end of the arm 27, will be held in its highest position thereby, Figs. 3 and 12, and while in such position the notch 126 in its side will receive the outer end of the pawl 119. The upper part of the bar 125 passes through a slot 127 in an arm 128, which projects radially from the sleeve 116 and is pressed toward the pawl 119 by a short pawl 129, pivoted at one end within the slot 127, and its free end held against the bar 125 by a spring 130 to hold it in contact with the pawl 119 while said pawl is engaged with the notch 126. The spring 130 is connected at 80 one end with a pin projecting from the free end of the pawl 129 through a curved slot 131 in the arm 128 and at its other end with a downwardly-projecting part of the arm 128. The initial movement of the treadle 26 in the direction shown by the full-line arrow at Figs. 12 and 19 will draw down the link-bar 125, and the upper side of the notch 126 will swing the pawl 119 downwardly and thereby swing the radial arm 118 downwardly and thrust 85 the prongs of the fork 120 through the holes 18 and nearly through the charge of stock within the adjacent mold, where the prongs will be momentarily held as the bar 125 is still farther lowered, by the side of said bar 90 being in sliding contact with the pawl 119, Fig. 19, until the bar 125 reaches the position shown at Fig. 20 and the treadle 26 has about completed its throw, when the pawl 129 will fall behind the cut-away part or recess 132 in the upper end of the bar 125 and thus allow 95 said bar to swing over toward said pawl and free the pawl 119 sufficiently to permit of it being raised, as shown at last-named figure, by a spring 133, which connects the arm 118 with a standard 134, projecting upwardly from a bracket 135, which projects from the sleeve 117, and which spring to raise the pawl 119, as described, acts on the rock-shaft 115 and thereby swings the arm 118 upwardly and 100 retracts the prongs of the transfixing-forks from the mold, Fig. 20. The return stroke of the treadle 26 in the direction of the arrow at Fig. 20 will move the link-bar 125 upwardly, and the shoulder at the lower side of the recess 132 will force the pawl 129 upwardly, (see dot lines at Fig. 20,) where it will 105 remain as said bar ascends to its normal position, Figs. 3 and 12, as the treadle 26 completes its return stroke, and the notch 126 is brought opposite the end of the pawl 119 and permits the bar 125 to be forced over by the spring-actuated pawl 129, and said notch again engaged with the pawl 119, ready for 110 another action on the transfixing-fork, when another mold is presented and detained by the detent 19.

The charge-gripping forks 136, one on the shaft 137 and the other on a similar shaft 138, are arranged in line with and one at each side of the mold which is at rest on the detent 19. Each fork 136 is removably fixed to its respective shaft by a bayonet-joint 139, Fig. 15. Preferably, each fork contains four prongs 130

140, arranged at the corners of a square with two of its opposite sides horizontal, Fig. 8, when the prongs enter the mold, so that they can enter it while the prongs of the transfixing-fork 120 are therein.

Immediately after the prongs 122 of the transfixing-fork have been lowered and thrust into the charge in a mold, as described, the prongs of the gripping-forks 138 are thrust into the charge in a mold from opposite ends of the charge as follows: The shaft 137 is mounted to reciprocate endlong and to rotate or oscillate in bearings 140 $\frac{1}{2}$ 141. The bearing 141 is a rotatable sleeve loosely mounted on said shaft and journaled in a bearing in a standard 141 $\frac{1}{2}$, Figs. 2 and 4. The shaft 138 is mounted to reciprocate endlong and to rotate or oscillate in bearings 142 143 in suitable standards, in one of which standards the rotatable sleeve-bearing 143 is itself journaled. The outer inturned end of the treadle-arm 27 is pivotally connected by a link 144, Fig. 15, with a radius-arm 145, which is fixed to a short shaft 146, the outer end of which carries a sector-gear 147, which gears with a pinion 148. One end of each of the similar connecting-rods 149 is pivotally connected with the pinion 148 at opposite sides thereof, and the other ends of the rods 149 are respectively hinged to blocks or bars 150, which are slidably mounted, one in each of the guideways 151. The blocks or bars 150 are connected at their other ends, one with the shaft 137 and the other with the shaft 138.

At Fig. 2 the pinion 148 is shown in its normal position and at Fig. 15 in its position after acted on by the arm 27 of the treadle 26 by means of their gear connection described. This movement of the pinion will draw the blocks 150 and shafts 137 138 toward each other and thrust the gripping-forks 136 into the mold and charge while the prongs of the transfixing-fork are still thereinto to hold the tobacco in place throughout the length of the charge and prevent it being pressed together or compacted by the action of the gripping-forks as they are thrust into the charge until their ends nearly or entirely meet or even pass each other, as will depend upon their lengths. While the gripping-forks are passing into the mold and charge said forks are alined to not contact with the transfixing-fork, as hereinafter described.

Immediately after the gripping-forks have entered the molds and the charge the transfixing-fork is retracted and its prongs 122 withdrawn therefrom by the action of the spring 133 as the treadle 26 reaches the end of its forward throw. The treadle 152 is journaled between its upper end or shorter arm and its lower end or longer arm on the shaft 1, and is shown in its normal position at Figs. 3, 5, 6, and 8. As soon as the transfixing-fork is withdrawn, as described, the treadle 152 is operated by the foot of the

same attendant who operates the treadle 26 now acting on the foot-piece 152 $\frac{1}{2}$. Limited oscillatory movement of the treadle 152 will 70 impart the necessary rotary movement to the gripping-forks for rotating the charge within the mold and thereby drawing the wrapper through the open side of the mold and thence between the charge and the wall of 75 the mold and wrapping it around the charge as it is drawn into the mold by the rotation of the charge to encircle and inclose the charge by the tube thus formed of the wrapper, as follows:

The short arm of the treadle 152 is a sector-gear 153 in gear with a small pinion 154, which is fixed to a larger pinion 155 and both journaled on the same short shaft 156, Figs. 2 and 6. The pinion 155 gears with a smaller pinion 157, which is loosely journaled on the shaft 138 and carries an annular flange 158, on the side of which is pivoted a spring-actuated pawl 159, Figs. 6 and 7, which engages with the ratchet-wheel 160 when the treadle 90 152 is given a return throw in the direction shown by the full-line arrows at Figs. 3, 5, and 6 and does not act on the ratchet-wheel when the treadle is given a throw in the opposite direction. The ratchet-wheel 160 is 95 fixed to the sleeve 141, and on the outer end of said sleeve is fixed a crown ratchet-wheel 161, which constitutes one member of a clutch 162, the other member of which is a collar fixed to the outer end of the shaft 138 and 100 provided with a tooth 164, adapted to engage, as shown by dot-lines at Fig. 2, with the teeth of the crown-wheel 161, when the shaft 138 is moved the limit of its throw toward the mold to thrust the gripping-forks into the charge, 105 as shown at Fig. 22. By short oscillatory movements of the treadle 152 the shaft 138 and the fork 136, which it carries, are now rotated intermittently in one direction, and the shaft 137 is rotated simultaneously therewith 110 by means of a rotatable shaft 165, which extends across the machine and carries a pinion 166, which gears with the pinion 167 on the sleeve 143, by which said pinion 166 and shaft 165 are rotated, and the other end part 115 of the shaft 165 carries a pinion 168, which gears with a pinion 169, fixed on the sleeve 141 to rotate said sleeve and the shaft 137, when the toothed collar 170 on the outer end of the shaft 137 is brought into engagement 120 with the other member 171 of the clutch 172 by the movement of said shaft toward the mold, as hereinbefore described.

The fork-shafts 137 and 138, Fig. 2, have each a collar 173 fixed thereon, from each of which collars a pointed cam 174 projects, Fig. 36. The standards 140 $\frac{1}{2}$ and 143 each have a sleeve 175 fixed thereto, through which sleeves the shafts 137 and 138, respectively, pass. Each sleeve 175 has V-shaped notches or cams 130 176 in its end facing the molds. As the shafts 137 and 138 are drawn backwardly away from the molds each pointed cam 174 enters one or the other of the V-shaped notches 176 in

the adjacent sleeve 175, and said notches are so located that when the pointed cam enters either of them the fork-shaft, if not in proper angular position, will be forced around to bring the prongs 140 at its next forward movement into proper positions for the passage therethrough of the prongs 122 of the charge-transfixing fork, as hereinbefore described. Stripping-brackets 177 are fixed, one to each standard *b*. Each stripping-bracket has a hole 178 in its downturned outer end, Figs. 9 and 11, which hole is in line with the adjacent end of each mold 16 as said mold is held at rest by the detent 19. The gripping-forks pass through the holes 178, and when withdrawn from the cigarette in the mold the bracket will strip the cigarette from the fork and prevent it being withdrawn from the mold by the fork.

20 Either tobacco-leaf or paper can be applied by this machine as wrappers. The wrappers, cut into form and ready pasted, are placed on the wrapper-table 180 by the attendant who operates the treadles 26 and 152. If the wrappers are in the form of a square (see dot-lines 181 at Fig. 11) or of a parallelogram, they are placed with their sides extending over or partly over the parallel grooves 182 in the wrapper-table 180. The grooves 182 are at right angles to the mold at rest on the detent 19, and the operator by pressing with the fingers slightly on the wrapper over said grooves and thereby forcing those parts of the wrapper into the grooves, which portions lie over the grooves, can utilize said grooves in feeding the wrapper properly to the mold, as the grooves will hold the wrapper in alignment with the table and mold. The wrapper is fed to the mold immediately after the gripping-forks have entered it and the transfixing-fork is withdrawn, and when the forward side of the wrapper has entered the open side of the mold and come into close contact with the charge in the mold then the operator or attendant gives a full forward throw to the treadle 152 to bring it into the position shown by dot-lines at Fig. 6. This throw of the treadle does not rotate the gripping-forks, but brings the end of the sector-gear 153 into contact with a foot 183, projecting from a short shaft 184, as a trip to partly rotate said shaft and turn the side tucker 185, which is fixed to said shaft, downwardly, Fig. 23, and into contact with the forward side of the wrapper 181. The treadle 152 is then given its return throw to rotate the charge in the mold, as before described, and thereby draw the wrapper around the charge, as shown partly completed at Fig. 24. When the treadle starts to make the throw last described, it will release the foot 183 and the spring 186 will restore the shaft 184 and side tucker 185 to their normal positions, where they are held by a detent-arm 187, which is pendent from the side-tucker arm and which when the side tucker is raised by the spring comes in contact with the shaft 165, Fig. 24.

The side tucker shown at Fig. 35 is best adapted by its longer lower side to act on the forward side of a square-shaped wrapper such as last described. When a wrapper 181 of a rhomboidal form is used, as shown by dot-lines at Fig. 1, then a side tucker with a narrow lower side is preferable, as shown in other figures, to engage merely with the forward point of such wrapper, which will in an evident manner be wound helically on the bunch.

To facilitate and aid in the wrapper being engaged by the charge when acted on by the side tucker, a roller 188 is journaled at its ends, 80 Fig. 25, in bearings 189, in a swinging frame 190, which is journaled by bearings 191 at its lower side to arms 191 $\frac{1}{2}$, pendent from the end of the wrapper-table confronting the molds. The swinging frame 190 is yieldingly held in its 85 normal position, Figs. 23 and 24, by a spring 192, which holds a pin 193, which projects from the swinging frame, in contact with a pin 194, which projects downwardly from the wrapper-table. The wrapper-table 180 is adjustable toward 90 and from the molds for the purpose of adjusting the position of the roller 188 relatively to the open side of the adjacent mold and in such manner that the roller rests in the open side of the mold with that part of its periphery which is next to the mold slightly within the mold, so that the roller will be pressed by the springs slightly into the side of the formed charge, while the mold is held at rest by the detent 19. The roller 188 when thus 100 held will, as the side tucker forces the edge or end of the wrapper down between the roller and the indent which it has made, as described, in the peripheral part of the formed charge, cause said charge with great certainty 105 to engage the side of the wrapper, whereby the wrapper will be drawn into the mold as the formed charge begins to rotate by the action thereon of the gripper-forks 140. The spring 192 permits the frame 190 and roller 110 188 to yield for the free passage of the outer ends of the jaws 11 and 12. The wrapper-table 180 is fixed after the adjustments referred to by set-screws 195, which pass through slots 196 in said table and into the frame- 115 work.

After the wrapper has been applied to a formed charge the mold containing the now completed cigarette S, Fig. 16, when released from the detent 19, moves to its next and lowest position, with its open or slot side downward, where it is detained by the detent 19, acting on the next succeeding mold, and while so detained the cigarette is ejected therefrom as follows: The ejector 197, Figs. 9 and 10, fitted to slide loosely through the molds, projects upwardly from a head 198, which is slidably mounted on guide-rods 199, Fig. 16. The head 198 is connected by a link-rod 200, Figs. 10 and 15, with a radius-arm 201, which is fixed to a rock-shaft 202, the outer end of which carries another radius-arm 203, which is connected by a link-rod 204 with one of the 120 125 130 135 140 145 150 155 160 165 170 175 180 185 190 195 200 205 210 215 220 225 230 235 240 245 250 255 260 265 270 275 280 285 290 295 300 305 310 315 320 325 330 these parts is such that as the treadle is given its throw to thrust the gripping-forks toward a mold the radius-arms 201 and 203 will be forced by the block 150 and link-rod 204 to 5 the respective positions shown by dot-lines at Fig. 10 and will carry the ejector with them by means of the link-rod 200 to its dot-line position shown at same figure. In passing to the last-named position the ejector will traverse the mold and force or eject the cigarette therefrom and onto a trough-shaped fixed guide 205, where it is received, and in 10 passing thereonto forces the last preceding cigarette S forwardly to the outer half 206 of said trough, which is cut away at one side, as shown at Fig. 17, in such manner that the cigarette, where shown by dot-lines at Fig. 16, can roll or slide laterally therefrom and onto the doffing-table, as hereinafter described. By the return stroke of the treadle 26 and while the mold it has passed through is still at rest the ejector is returned to its 15 normal position (shown by full lines at Figs. 10 and 16) and ready for operation on the cigarette contained in the next succeeding mold.

Before the ejector reaches the mold as it is moved toward it the swinging jaw of the mold is drawn back to slightly separate the jaws 30 11 and 12 and free them, so as to release the cigarette and render it easily ejected, but not open them to such extent as to permit the cigarette to fall out of the mold. This slight opening of the jaws is effected as follows: A 35 U-shaped frame 207, Figs. 8, 9, 10, and 16, is pivotally connected at the upper end of its vertical arms 208 to the standards b to permit of its swinging to carry its lower horizontal part or bar 209 toward and from the 40 head 198. A yielding spring-arm 210 projects laterally from one of the arms 208 into the orbital path of the pins 90, which project from the hinged jaws 12. The arm 210 has a tapering head and catch 211 on its outer end. 45 A spring 212, fixed at one end to one of the standards b and at its other end to the lower part of the frame 207, holds said frame with a yielding force in its normal position, Figs. 12 and 16, with the friction-roller 213, carried 50 by the head 198, resting against the lower bar 209 at the back of the recess 214 in said bar. When the ejector starts to move, the roller 213 will pass from the recess 214 into contact with the full bar 209 and thereby force the frame 207 backwardly and thus draw back the arm 210, and the catch 211, being engaged with the 55 pin 90 of the lower mold, will draw back the hinged jaw thereof and slightly open the mold. The roller 213 will remain in contact with the bar 209 until the ejector is again 60 returned to its normal position described. The mold from which the cigarette has been removed then moves forward in its orbital path and carries the pin 90 away from the catch 65 211. As the next succeeding mold now approaches its lower position its pin 90, coming in contact with the sloping head of the yield-

ing spring-arm 210, will press it downwardly and pass thereover to the catch 211, which will then engage with the pin 90 as the mold 70 comes to rest and be in position for slightly opening it, as described in reference to the last preceding mold.

When the cigarette rolls or slides from the part 206 of the trough 205, as before described, 75 it is received on the lower end of an inclined plate or table 215, Fig. 17, and retained thereon by the upturned ledge 216 until said table is tripped or turned on its pivotal shaft 217 to lower the ledge 216 below the surface 80 of the upper end of the inclined slideway 218, (see dot-lines at same figure,) and thereby allow the cigarette to roll or slide from the table 215 onto the slideway 218, over which it will roll or slide down to any suitable receiver. 85 (Not shown.) The slideway 218 is connected with or hinged also to the shaft 217 and held in place by a spring 219. The plate or table 215 is tripped or tilted, as described, by means of a tappet 220, Figs. 15, 17, and 18, which 90 tappet is fixed to the inner side of one of the sliding blocks or plates 150 in such position relatively to a tripping-cam 221 on the lower side and outer end of the table 215 that as the gripping-forks are withdrawn from the 95 mold by the backward movement of the blocks 150 the tappet 220 will come in contact with the lower and inclined side of the cam 221, and thereby tip or tilt the table 215 into the position shown by dot-lines at Fig. 100 17, and thus lower the ledge 216 below the upper surface of the upper end of the slideway 218, for the purpose of doffing the cigarette as hereinbefore described. As the treadle 26 is given its forward stroke and the 105 blocks move toward the molds and just before the ejector operates to discharge a cigarette, the tappet passes from beneath the cam and the spring 219, tilts the table 215 to lower 110 its outer end and raise the ledge 216 on its upturned lower end to receive and retain said cigarette until the table 215 is again tilted by the tappet to doff or discharge the cigarette over the inclined table 218, as hereinbefore described. 115

I desire it understood that I do not limit my claims to the details of construction shown, in which I have simply illustrated one way of embodying the creative part or conception of the invention in a concrete form in a structure or machine. The described devices are simply embodiments of the invention which other structures might also embody, and some of the parts, as also combinations of parts, may be used without the others in different types 120 of such machines without departure from the purview of my invention, and I regard myself as entitled to such variations from the shown and described devices as fall within the scope of my invention as expressed in the claims 125 hereto appended.

What I claim as new is—

1. In a cigarette-machine, and in combination substantially as described, a circular se-

ries of molds each having an open side, means for revolving said molds, means for intermittently arresting their revolving motion, a vertically-reciprocating frame, a frame hinged to 5 said reciprocating frame so that it can swing forwardly, a cam-shaft having cams for reciprocating said frame, and others for swinging said swinging frame, a cutter-blade fixed to said swinging frame whereby the cutter-blade 10 is moved vertically to sever the charges of tobacco stock and swung forwardly to force said charges successively to the molds, mechanism for placing the wrappers on the charges which have been previously formed in the 15 molds, and an ejector for discharging the completed cigarettes from the molds, all acting with the molds in the order recited and at different places in their common orbital path.

2. In a cigarette-machine, and in combination substantially as described, a circular series of molds, each having an open side, means for revolving said molds, means for intermittently arresting the motion of said molds, means for opening said molds, a frame which 25 is movable vertically, means for reciprocating said frame, a swinging frame hinged to said reciprocating frame, carrying a cutter-blade which moves vertically with the swinging frame to sever the material, and swings 30 forwardly therewith to force the material into the molds successively, means for swinging said frame and cutter-blade, a mold-opener, means for closing said molds, mechanism for placing the wrappers on the charges while in 35 the molds and which have been previously formed in the molds, and an ejector for discharging the completed cigarettes from the molds, all acting on each mold in the order recited and at different places in their common orbital path, except the swinging frame or feeder and mold-opener, which act on the 40 molds at the same place in their common orbital path.

3. In a cigarette-machine, and in combination substantially as described, a rotating head, a charge-forming mold comprising two substantially radial jaws with confronting grooves, one of which jaws is hinged to the 45 rotating head in such manner that said jaws may be closed to form the mold in which the charges are given form, and may be opened to admit the unformed charges of stock, or for other purposes, and a diaphragm, fixed to 50 one of said jaws, and a recess in the confronting jaw in which said diaphragm slides back and forth as the jaws are opened and closed respectively.

4. In a cigarette-machine, and in combination substantially as described, a series of revolving molds each having a slotted or open side, an intermittent feeding mechanism 60 which carries a regulated sheet of tobacco stock, a reciprocating cutter with a swinging cutter-blade hinged thereto and forming a 65 part thereof, for severing said stock into regulated quantities for each charge, means for reciprocating said cutter, and means for

swinging said cutter-blade forwardly to force the severed stock into the mold.

5. In a cigarette-machine and in combination substantially as described, a revolving series of molds, a reciprocating frame with pendent side arms, a cam-shaft with a cam which acts on said arms to force the frame downwardly, a cutter-blade frame hinged to 70 said armed frame and forced downwardly and upwardly thereby for severing charges of tobacco from a regulated sheet, cams on said cam-shaft which cams act on arms pendent from said cutter-frame and swing it forwardly to feed such charge into a mold, and a mold-opener comprising a pendent arm with a catch, a shaft which carries it, an arm projecting from said shaft radially, and a cam mounted on said cam-shaft. 75

6. In a cigarette-machine, and in combination substantially as described, a revolving series of molds each having an open side, a reciprocating cutter-frame with pendent side arms, a cam-shaft with a cam which acts on 80 said arms to force the cutter downwardly for severing charges of tobacco from a regulated sheet thereof, a swinging cutter-blade-carrying frame hinged to said reciprocating frame, cams on said cam-shaft which force the cutter-blade and swinging frame forwardly, to feed such charges into a mold, a mold-opener, comprising a pendent arm with a catch, a shaft which carries it, an arm projecting from 85 such shaft radially, and a cam mounted on said cam-shaft. 90

7. In a cigarette-machine and in combination substantially as described, a series of revolving molds each with a slotted or open side, an intermittent feeding mechanism 95 which carries a regulated sheet of tobacco stock, a reciprocating frame, another frame which moves vertically with said reciprocating frame which is hinged thereto and carries a cutter-blade for severing said stock into regulated quantities for each charge, means for reciprocating said cutter, and means for swinging said cutter-blade forwardly to force the severed tobacco stock into the molds. 105

8. In a cigarette-machine and in combination substantially as described, a revolving series of molds, a reciprocating cutter-frame with pendent side arms, a swinging frame hinged to said cutter-frame and carrying a cutter-blade, cams on a cam-shaft which act 110 on said side arms to move said cutter-frame downwardly, means for moving said cutter-frame in an opposite direction, cams on said cam-shaft for swinging the cutter-blade and swinging frame forwardly to force said charges into the mold, means for returning said swinging blade and swinging frame to their normal positions, a clutch mechanism mounted on said cam-shaft, and a main drive-shaft from which said cam-shaft receives motion. 115

9. In a cigarette-machine, and in combination substantially as described, a revolving series of molds, a reciprocating cutter-frame

with pendent side arms, a swinging frame hinged to said cutter-frame and carrying a cutter-blade, cams on a cam-shaft which act on said pendent side arms to move the cutter-frame downwardly, springs for moving said cutter-frame upwardly, cams on said cam-shaft for swinging the cutter-blade and swinging frame forwardly, to force said charges into the mold, other springs for returning said blade to its normal position, a mold-opener, a cam on said cam-shaft for moving said mold-opener in one direction to open a mold, and a spring for moving the mold-opener in an opposite direction to release the mold from said opener to permit of closing the mold.

10. In a cigarette-machine, and in combination substantially as described, a revolving series of molds, each of which molds has a hinged jaw, a spring for closing said jaws or molds, a lug or pin projecting from each hinged jaw, and a mold-opener comprising an arm with a catch which engages with said lug or pin for opening the mold.

11. In a cigarette-machine and in combination substantially as described, a revolving series of molds, each of which has a hinged jaw, a spring for closing said jaws or molds, a lug or pin projecting from each hinged jaw, a mold-opener comprising an arm with a catch which engages with said lug or pin, a shaft with a cam for operating said arm in one direction, and a spring for moving it in a reverse direction.

12. In combination, a series of intermittently-revolving molds, compacting-arms, one at each open end of one of said molds while at rest, a reciprocating cutter-blade having lugs which force the compacting-arms outwardly in its descent, and springs which force the compacting-arms inwardly toward the mold, substantially as described.

13. In combination, a series of intermittently-revolving molds, compacting-arms, one at each open end of one of said molds while at rest, a reciprocating cutter-blade having lugs which force the compacting-arms outwardly in its descent, springs which force the compacting-arms inwardly toward the mold, and trough-shaped guards which hold the tobacco projecting from the ends of the mold, from falling until it is acted on by the compacting-arms, substantially as described.

14. In combination with a series of revolving molds, a reciprocating cutter-blade hinged to swing as a force feeder of a charge of stock to each mold, an intermittently-moving feed-belt, compressor-rolls, a compressor-block having pendent arms, and a cam-shaft having cams which act on said arms to raise the presser-block, substantially as described.

15. In a cigarette-machine, and in combination substantially as described, a series of revolving molds, a reciprocating frame with pendent arms, a cutter-blade frame hinged to said main frame and having pendent arms, a compressor-block also having pendent arms, a mold-opener fixed to a rock-shaft which

carries a radial arm, and a cam-shaft having cams for forcing said reciprocating frame and cutter-blade downwardly, cams for swinging 70 said cutter-blade and frame, cams for elevating the compressor-block and a cam for actuating said mold-opener.

16. In a cigarette-machine, and in combination substantially as described, a series of revolving molds, a reciprocating frame with pendent arms, a cutter-blade frame carrying a cutter and hinged to said reciprocating frame and provided with pendent arms, a compressor-block also having pendent arms, 80 a mold-opener fixed to a rock-shaft which carries a radial arm, a cam-shaft having cams for forcing said reciprocating frame and cutter-blade downwardly, cams for swinging 85 said cutter-blade and frame, cams for elevating the compressor-block, and a cam for actuating said mold-opener, a clutch mounted on said cam-shaft and geared with a clutch mechanism mounted on the mold-shaft whereby said cam-shaft is given as many intermittent 90 rotations by each rotation of the mold-shaft as there are molds carried by said shaft.

17. In a cigarette-machine, and in combination substantially as described, a series of revolving molds, a reciprocating frame with 95 pendent arms, a cutter-blade frame carrying a cutter and hinged to said reciprocating frame and provided with pendent arms, a compressor-block also having pendent arms, a mold-opener fixed to a rock-shaft which carries a radial arm, feed-rollers, a ratchet-wheel fixed to one of the belt feed-rollers, a crank-arm loosely mounted on the end of said roller-shaft, a spring-actuated pawl, pivoted to said crank-arm, a link-rod, a cam-shaft having 105 cams for forcing said reciprocating frame and cutter-blade downwardly, cams for swinging said cutter-blade and frame, cams for elevating the compressor-block, a cam for actuating said mold-opener, a feed-belt, and a cam 110 for acting on said link-rod to give an intermittent forward motion to the feed-belt.

18. In a cigarette-machine, the combination comprising a feed-belt passing between rollers, pinions for gearing said rollers to each 115 other, a ratchet-wheel fixed to the shaft of one of said rollers, a crank-arm loosely mounted on said shaft and provided with a pawl engaging said ratchet-wheel, a link-rod, a cam on a rotating shaft for drawing said 120 crank-arm in one direction, and a spring for returning it in an opposite direction, and a catch hinged to said link-rod and adapted to engage with a shaft or rod for holding the link-rod out of contact with the cam on the 125 cam-shaft whereby the movement of the feed-belt is arrested, substantially as described.

19. In a cigarette-machine, the combination comprising a continuously-rotating drive-shaft, a mold-carrying shaft in gear with said 130 drive-shaft, a friction-clutch on said mold-carrying shaft consisting of a pinion loosely mounted on said shaft and a disk fixed on said shaft and provided with radial lugs, a

cam-shaft with a clutch thereon consisting of a ratchet-faced pinion loosely mounted on said shaft and in gear with the drive-shaft and a disk fixed thereon which disk carries a 5 spring-pawl, and a trip mechanism actuated by said radial lugs to throw the clutch on the cam-shaft into engagement, substantially as described.

20. In a cigarette-machine, and in combination, a continuously-rotating drive-shaft, a mold-carrying shaft in gear therewith, a clutch on said mold-carrying shaft, a cam-shaft, a clutch on said cam-shaft, and a trip actuated by the clutch on the mold-shaft, for throwing the clutch into engagement on the cam-shaft, substantially as described.

21. In a cigarette-machine, the combination, a rotating shaft carrying a series of molds, a rock-shaft, a detent fixed to said rock-shaft, 20 an oscillatory treadle and pawl, a ratchet-wheel actuated by said pawl, and a pawl fixed to the detent-carrying shaft at one end and at its other end in contact with said ratchet-wheel, whereby it is oscillated to swing the detent into and out of the orbital paths of the molds, substantially as described.

22. In a cigarette-machine, and in combination, a rotating shaft carrying a series of molds, a rock-shaft, a detent fixed to said rock-shaft, an oscillatory treadle, means whereby said treadle intermittently swings the detent into and out of the orbital path of the molds, a drive-shaft, and a friction-clutch on the mold-shaft, which slips to throw the mold-shaft out of gear with the drive-shaft when the detent engages a mold, and engages by friction to throw the mold-shaft into gear with the drive-shaft when the detent is disengaged with any of the molds, substantially 40 as described.

23. In a cigarette-machine, and in combination, an intermittently-rotating shaft carrying a series of molds, a rock-shaft, a detent fixed to said rock-shaft, an oscillatory treadle, 45 means whereby said treadle intermittently swings the detent into and out of the orbital paths of the molds, a drive-shaft, a friction-clutch on the mold-shaft whereby said shaft is thrown out of gear with the drive-shaft 50 when the detent engages a mold, and in gear with said shaft when the detent is disengaged from a mold, a cam-shaft, a clutch on said cam-shaft, and a trip actuated by the mold-shaft for operating said clutch whereby said cam-shaft is intermittently rotated by the 55 drive-shaft to impart movement to the feed-belt, the cutter, the presser-block and the compacting-arms during the intervals of rest of the molds, substantially as described.

60. 24. The combination in a cigarette-machine, of a drive-shaft, a mold-carrying shaft, a detent for intermittently arresting the revolving motion of the molds, treadle 26, pawls 28 and 32, spring 33, ratchet-wheel 31, and a 65 friction-clutch on said mold-shaft, by which it is geared with the drive-shaft, substantially as described.

25. In a cigarette-machine, in combination, a mold with a series of holes through one side thereof, a charge-transfixing fork with a series of prongs corresponding with the holes in the mold, a rock-shaft with a radial arm with which said transfixing-fork is connected, an oscillating treadle, and means for transmitting motion from said treadle to said rock-shaft and transfixing-fork, substantially as described. 70

26. In a cigarette-machine, in combination, a mold with a series of holes through one side thereof, a charge-transfixing fork with a corresponding series of prongs, and means for thrusting said prongs through said holes and through the charge of tobacco stock contained in the mold, substantially as described. 80

27. In a cigarette-machine, the combination, 85 comprising an intermittently-rotating series of molds, each mold having a series of holes through one side of the wall thereof, a transfixing-fork hinged to a bar projecting from a rock-shaft, a second radial bar fixed to said rock-shaft, a treadle, a bar projecting from said treadle, means connected with said radius-bar and bar projecting from the treadle whereby said treadle thrusts the transfixing-fork prongs through said series of openings, 95 and a spring for giving the transfixing-fork a reverse movement and withdrawing its prongs from the series of holes, substantially as described.

28. In a cigarette-machine, and in combination, a mold with a series of holes or openings through one side thereof, gripping-forks having a reciprocating and rotary movement, which enter the ends of the mold and the charge for rotating the charge, a charge-transfixing fork with a series of prongs, and means for thrusting said prongs through said openings or holes and through the charge in the mold, and retaining them there until the gripping-forks are inserted in the charge and then withdrawing the transfixing-fork prongs, substantially as described. 105

29. In a cigarette-machine, in combination substantially as described, a mold with a series of openings or holes through one side 115 thereof, a transfixing-fork having a reciprocating movement to thrust its prongs through said openings or holes and withdraw them, and gripping-forks having a reciprocating and a rotary motion, substantially as described. 120

30. In a cigarette-machine, and in combination, a series of intermittently-revolving molds, a charge-transfixing fork, gripping-forks, and means for both reciprocating and rotating said gripping-forks, substantially as 125 described.

31. In a cigarette-machine, and in combination, a series of intermittently-revolving molds, a charge-transfixing fork and means for operating it, gripping-forks reciprocated 130 by sliding blocks, connecting-rods, an oscillating pinion, a rock-shaft, a radius-arm, a treadle, and a link-rod connecting said treadle and radius-arm, substantially as described.

32. In a cigarette-machine, and in combination substantially as described, a series of intermittently-revolving molds, gripping-forks, a detent for arresting the revolving motion of the molds, and a treadle which operates said detent and reciprocates the gripping-forks.

33. In a cigarette-machine, and in combination substantially as described, a series of intermittently-revolving molds, a charge-transfixing fork, gripping-forks, a detent for arresting the revolving motion of the molds, and a treadle which operates said detent and the charge-transfixing fork and reciprocates the gripping-forks.

34. In a cigarette-machine, and in combination substantially as described, a series of intermittently-revolving molds, a cutter-blade and means for swinging said blade to force a charge of stock severed by the cutter-blade through the open side of a mold, a detent for arresting the revolving motion of the molds, gripping-forks, and a treadle which operates the detent and reciprocates the gripping-forks, all of which are so timed in their movements in relation to each other that the cutter-blade is acting as a feeder to one mold while the gripping-forks are operating on another mold.

35. In a cigarette-machine, and in combination substantially as described, a series of intermittently-revolving molds, a cutter-blade and means for swinging said blade to force a charge of stock severed by the cutter-blade through the open side of a mold, a detent for arresting the revolving motion of the molds, gripping-forks, a charge-transfixing fork, and a treadle which operates the detent and the transfixing-fork and reciprocates the gripping-forks, all of which are so timed in their movements in relation to each other that the cutter-blade is acting as a feeder to one mold while the transfixing-fork and gripping-forks are operating on another mold.

36. The combination comprising, a mold, a charge-transfixing fork, gripping-forks having both rotary and reciprocating motion, and means for alining the gripping-forks with the transfixing-fork, substantially as described.

37. The combination in a cigarette-machine, comprising a mold with an open side, means for rotating the charge of tobacco therein, a wrapper feed-table, and a roller journaled in bearings at the side of said table which confronts the open side of the mold, substantially as described.

38. In a cigarette-machine, and in combination, substantially as described, a mold with an open side, means for rotating a charge of tobacco therein, an adjustable wrapper feed-table, a roller, a swinging frame in which said roller is journaled, and a spring and stop which hold said frame and thereby hold the roller with a yielding force in substantially the position described, with reference to the open side of the mold.

39. In a cigarette-machine, and in combination substantially as described, a mold with

an open side, means for rotating a charge of tobacco therein, an adjustable wrapper feed-table, and a roller journaled in yielding bearings at the side of the wrapper-table confronting the open side of the mold.

40. In a cigarette-machine, and in combination substantially as described, a mold, a wrapper feed-table, a side tucker adapted to feed the forward edge of the wrappers into the open side of said mold and onto the periphery of the charge contained therein while the charge is in the mold, and gripping-forks for then rotating the charge and coiling the wrapper thereon.

41. In combination in a cigarette-machine, substantially as described, a revolving series of molds, a feed-table, a yielding roller located between said feed-table and said mold with its periphery in the open side of said mold and slightly pressed into the charge, and a reciprocating tucker for forcing the forward edge of the wrapper between said roller and the charge.

42. In a cigarette-machine, and in combination substantially as described, a mold with an open side, an adjustable wrapper feed-table, a yielding roller journaled in bearings at that side of said table which confronts the open side of said mold, a side tucker for forcing the edge of the wrapper between the roller and charge in said mold, and forks which are rotatable to rotate the charge and thereby further draw the wrapper into the mold to encircle the charge and complete the cigarette.

43. In a cigarette-machine and in combination, substantially as described, a mold with an open side, a wrapper feed-table, a roller journaled in bearings at that side of said table which confronts the open side of the mold, a side tucker for forcing the edge of the wrapper between the roller and charge in said mold, and forks which are rotatable to rotate the charge and thereby further draw the wrapper into the mold to encircle the charge and complete the cigarette.

44. In a cigarette-machine, and in combination with intermittently-revolving molds, reciprocating shafts carrying charge-gripping forks, one member of a clutch fixed to the outer end of each fork-shaft, another tubular member thereof for each fork-shaft, journaled each in a support, and one of said shafts journaled in each of said tubes or sleeves, and a shaft carrying a pinion on each of its ends, one of which pinions gears with a pinion on each of said tubes or sleeves for simultaneously rotating said fork-shafts.

45. In a cigarette-machine, and in combination with intermittently-revolving molds, reciprocating shafts carrying charge-gripping forks, one member of a clutch fixed to the outer end of each fork-shaft, another tubular member thereof for each fork-shaft, journaled each in a support, and one of said shafts journaled in each of said tubes or sleeves, a shaft carrying a pinion on each of its ends, one of which pinions gears with a pinion on each of

said tubes or sleeves for simultaneously rotating said fork-shafts, a pinion on one of said sleeves, a disk carrying a ratchet engaging with said pinion, a pinion fixed to the side 5 of said disk, a larger pinion geared therewith, a small pinion fixed to said larger pinion, and a treadle with a sector-gear for oscillating said pinions and the rock-shafts.

46. In a cigarette-machine, and in combination substantially as described, an intermittently-revolving series of molds with a slot or opening in one side of each mold, means for forcing a charge of stock into each of said molds, shafts, each carrying a gripper-fork, 15 rotating sleeves, one for rotating each shaft, said shafts having endlong movement in said sleeves respectively, and means for rotating said sleeves intermittently.

47. In a cigarette-machine, and in combination, substantially as described, an intermittently-revolving series of molds each having 20 an open side, an ejector, slidably mounted on guides and projecting through said open side into a mold while the molds are at rest 25 and the ejector in operation, and means for reciprocating the ejector on said guide rods or ways.

48. In a cigarette-machine, and in combination, substantially as described, an intermittently-revolving series of molds each having 30 an open side, an ejector slidably mounted on guides and projecting through said opening and into a mold while the molds are at rest and the ejector in operation, and means 35 gearing the ejector with the same treadle which operates the gripper-forks and transfixing-fork.

49. In a cigarette-machine, and in combination substantially as described, an intermittently-revolving series of molds, each mold 40 formed of jaws with confronting grooves and one of which jaws is hinged to open the mold, a reciprocating ejector, and a mold-opener operated by the initial movement of the ejector to open the mold slightly and free the cigarette 45 immediately before the ejector acts on the cigarette.

50. In a cigarette-machine, and in combination substantially as described, an intermittently-revolving series of molds, each mold 50 formed of jaws with confronting grooves and one of which jaws is hinged to open the mold, a reciprocating ejector, and means for actuating the ejector, and a mold-opener com-

prising a swinging frame, a spring-arm having 55 a sloping head and catch fixed to said swinging frame, a bar fixed to said frame, with a recess at one end, a roller journaled in the head of the ejector, a lug or pin projecting from the hinge-jaw of the mold, and means for operating the ejector which ejector operates the mold-opener immediately before it enters the mold.

51. In a cigarette-machine, and in combination substantially as described, an intermittently-revolving series of molds, an ejector for pushing the completed cigarette endlong 65 from a mold during its interval of rest, a trough-shaped receiver for the cigarette with one side of its outer half removed, a tilting 70 table with its lower side turned up to form a ledge for retaining the cigarette on the outer part of said trough, means for tripping or tilting said table to lower said ledge for the escape of the cigarette, and an inclined table 75 for receiving the cigarette and carrying it to any suitable receiver.

52. In a cigarette-machine, a combination comprising an open-side mold, an ejector, a trough constructed substantially as described, a tilting table with a ledge at its lower side and a cam at its opposite side or end, a tappet fixed to one of the arms or blocks which reciprocate the gripping-forks, whereby said table will be tilted to doff a cigarette 85 as said forks are withdrawn from the mold, and a spring for restoring said table to its normal position.

53. In a cigarette-machine and in combination substantially as described, a revolving 90 series of molds each open at one side, a reciprocating frame with pendent side arms, means for reciprocating said frame, a swinging arm pivotally connected with the upper part of said frame and other swinging arms 95 or links pivotally connected with its lower end for alining its movements, a swinging frame carrying a cutter-blade, hinged to said reciprocating frame to swing forwardly, and means for swinging said swinging frame, substantially as described.

In testimony whereof I affix my signature in presence of two witnesses.

GEORGE GEER.

Witnesses:

E. S. BLANTON,
H. R. POLLARD, Jr.

It is hereby certified that the name of the assignee in Letters Patent No. 593,158, granted November 2, 1897, upon the application of George Geer, of Richmond, Virginia, for an improvement in "Cigarette Machines," was erroneously written and printed "Charles E. Buck," whereas said name should have been written and printed *Charles E. Buek*; and that the said Letters Patent should be read with this correction therein that the same may conform to the record of the case in the Patent Office.

Signed, countersigned, and sealed this 16th day of November, A. D. 1897.

[SEAL.]

WEBSTER DAVIS,
Assistant Secretary of the Interior.

Countersigned:

A. P. GREELEY,
Acting Commissioner of Patents.
